UNITED STATES PATENT OFFICE.

SCOTT JENKS, OF CHESHIRE, MASSACHUSETTS, AND HENRY W. MILLAR, OF UTICA, NEW YORK, ASSIGNORS TO SAID JENKS, AND CHARLES & HENRY W. MILLAR, OF UTICA, NEW YORK.

CHEESE-MAKING APPARATUS.

SPECIFICATION forming part of Letters Patent No. 283,250, dated August 14, 1883.

Application filed February 9, 1883. (No model.)

To all whom it may concern:

Be it known that we, SCOTT JENKS, of Cheshire, Berkshire county, Massachusetts, and HENRY W. MILLAR, of Utica, Oneida county, New York, citizens of the United States, have invented new and useful Improvements in Cheese-Making Apparatus, of which the following is a specification.

Our invention relates to apparatus for manipulating curd cutters and agitators in the art of making cheese; and the novelty consists in the construction, arrangement, and adaptation of parts, as will be more fully hereinafter set forth, and specifically pointed out in the 15 claims.

The essential features of the invention, among others, may be briefly stated to be, first, to provide a construction which allows the cutters of two or more vats to be operated 20 from a single power-shaft, all the cutters traversing the vats simultaneously in one direction; second, to allow the cutters or agitators of a series of vats to be impelled rotarily and reciprocally in opposite directions at the same 25 time; and, third, to so construct the vertical rotating shafts, which carry the cutters, that one or more of said cutters of a series of cutters may be disengaged from its bearings—as, for instance, when its appropriate vat or pan 30 is not in use.

The invention is designed as an improvement upon the device set forth in patent granted to Scott Jenks, one of these joint inventors, November 7, 1882, No. 267,211, and 35 it is fully illustrated in the accompanying drawings, which form a part of this specification, and in which—

Figure 1 is a plan view illustrating three vats, the cutters of each being operated by a 40 single shaft mounted above the center vat; Fig. 2, a plan view of a similar series, the cutters of each being operated from a single shaft, and all hung upon a rigid frame; Fig. 3, a plan view of a similar arrangement with chain 45 and sprocket connections substituted for the rigid frame. Fig. 4 is an elevation with the vat or pan in section, showing a bevel-gear connection between the horizontal power-shaft and the rotary suspension-shaft, which carries

the cutters; Fig. 5, an enlarged face view of 50 such bevel-gear connections, showing the connection also between the suspension-shaft gear and longitudinal rack-bar; Fig. 6, a transverse section of the same. Fig. 7 is a detail view, showing the connections illustrated in Fig. 3; 55 and Figs. 8 and 9 are detail views, illustrating the means for engaging and disengaging the curd cutters or agitators from the rotary suspension-shafts.

In the patent hereinbefore mentioned the 60 cutter was rotated and reciprocated in a pan or vat of width approximating the width of swath made by the cutters. In an application filed of even date herewith the cutters made two swaths to accommodate a larger pan or 65 vat, and in the present application the construction and advantages set forth in the patent are multiplied—that is to say, the reciprocating rotating cutters are used in series, and all are operated from a single shaft. 70

Referring to the drawings, in which similar letters of reference indicate like parts in all the figures, A indicates the vats, each of which is provided with the ordinary heating-pipes, a.

B indicates the pendent cutter-frame, carrying the curd-cutters b, and said frame is removably secured to the lower portion of the removable portion of the rotating suspension-shaft C, as shown. This portion of said shaft is connected to the upper portion by inclined 80 joint C² and hooks c⁶, which engage lugs or pins c⁷. Ears c⁸ are provided on each portion, and through perforations in these ears operates a bolt, c⁹, having a collar, c⁸, and an operating-projection, c¹⁰. A spiral spring, bearing between the collar c⁸ and box c¹¹, serves to hold with a constant force the bolt c⁹ in locking position in the perforated ears c⁸. This construction allows the ready disengagement of either 85 of the curd-cutters in the series when desired—90 as, for instance, when one of the vats or pans is being drawn off or is not in use, and when such disengagement has taken place the remaining portion of the suspension rotary shaft C revolves and reciprocates idly. 95

Referring to Figs. 4, 5, and 6, at the upper portion of the shaft C is jointed or swiveled a section carrying a gear, C', having a beveled

portion which meshes with the beveled gear J, which has an internal lug which traverses and reciprocates in a longitudinal groove, i, in the shaft I. This gear C' has also a cylindrical gear portion, J', which meshes with the rack-bar K, and the shaft of this said gear C' is journaled in a carriage, D, which traverses the shaft I. This carriage D holds the gears J C' in constant mesh, and as the power-shaft 10 is rotated by means of pulley f and power-connections the gear C' is made to traverse the rack in one direction, at the same time rotating the cutters until the belt is tripped or shifted by the carriage D striking one of the 15 triggers, m, on the sliding rod M, as is fully explained in the patent hereinbefore referred to. This construction of operating devices we prefer to apply to either of the arrangements of connecting devices shown in Figs. 1, 2, and 3; 20 but these said connecting devices with other vats may be used with equal efficiency in connection with the screw-rod F.

In Fig. 1 we show three vats, A, the cutters for the center one being operated by a screw-rod, F, having pulley attachment f. To the carriage D, which is forced to traverse the longitudinal plane of the vat or pan, are secured ropes d, which, passing through proper pulleys, d', in opposite directions, are in turn secured to the side carriages, D'; hence when the carriage D is making its traverse in the direction shown by the arrow the carriages D' are making their traverse in an opposite direction. Each of the carriages carries the traversing-pinion c', which, engaging the rack-bar K, causes the rotation of the cutter-shaft and cutters. In Fig. 2 we illustrate a rigid frame, G, which connects all the carriages of the series; but in other respects the operation is the same, except that the several carriages move together in the same direction. In Fig. 3 is shown another and different arrangement. Upon the shaft which carries the rack-engaging pinion C', above and below the horizontal plane of said rack, is secured a sprocket-wheel, h, and endless chains H H connect with similar sprockets, h, upon the vertical suspension-shafts C of the side cutters, or the cutters which operate in the side vats respectively. 45 A detached view, Fig. 7, fully illustrates this part of the invention, and it will be observed that in this construction all the carriages move together in the same direction. The belt-shifting rod and triggers M m are used in each 50 and all of these constructions for the purpose of stopping the carriages when they have completed their traverse in one direction, and starting them on their return traverse or reciprocation. It will be understood that either of the arrangements shown in Figs. 1, 2, and 3 may be used, and that either the screw-rod or the mechanism shown in Figs. 4, 5, and 6 may be employed in connection therewith.

Modifications in details of construction may 65 be made without departing from the principle or sacrificing the advantages of our invention, the essential features of which will be readily

understood from the foregoing description, taken in connection with the drawings, and the operation of the several parts will be obvious to those skilled in the art to which the invention relates. 70

Having thus described our invention, what we claim is—

1. In an apparatus for cutting and agitating curd in the art of making cheese, a series of suspension rotary shafts carrying cutters or agitators, combined with a single actuating power-shaft, and with means, substantially as described, for imparting to each cutter-shaft 75 a rotary motion, and to said cutter-shafts reciprocating motions, as and for the purposes specified.

2. In an apparatus for cutting and agitating curd in the art of making cheese, a series of suspension rotary shafts carrying cutters or agitators, combined with a single actuating power-shaft, and with means, substantially as described, for imparting to each cutter-shaft 85 a rotary motion, and to said cutter-shafts a reciprocating motion simultaneously in the same direction, as and for the purpose specified. 90

3. In an apparatus for cutting and agitating curd in the manufacture of cheese, and in combination with a series of pans or vats arranged substantially as shown, a series of rack-bars, a corresponding number of suspension rotary shafts carrying cutters or agitators, and each shaft carrying a pinion adapted to engage and traverse its appropriate rack-bar, carriages supporting said rotating shafts, rigid connections between such carriages, and a single actuating power-shaft, as and for the purpose described. 95

4. In the art of cheese making, a series of 105 revolving suspension-shafts carrying cutters or agitators adapted to traverse and revolve in a series of vats, in combination with a single actuating power-shaft, means for connecting the suspension-shafts therewith, and means for securing or removing one or more of the cutters at will, as set forth. 110

5. In a cheese-making apparatus, and in combination with a rotary shaft carrying a cutter or agitator, and having a beveled gear, with cylindrical portion j', a longitudinally-grooved power-shaft, a feathered beveled gear operating loosely thereon, a traversing-carriage for holding the gears in mesh with each other, and the gear C' in mesh with a longitudinal 115 rack-bar, substantially as described. 120

6. In a cheese-making apparatus, and in combination with a series of suspension rotary shafts carrying cutters or agitators, and connections therefrom, with a central carriage, a power-shaft having a longitudinal groove, a feathered beveled gear revolving with and loosely traversing said power-shaft, a gear-wheel having a bevel and a cylindrical gear-surface, and a longitudinal rack-bar, substantially as described. 125

7. The shaft C, made in sections and having inclined joint C², the perforated ears c', box c', hooks c⁶, pins c⁷, bolt c² c³ c⁸, and spring c⁵, all 130

constructed and arranged as set forth, for the purpose specified.

8. The power-shaft I, having longitudinal groove *i*, the carriages D and D', the loose bevel-gear J, the gear C', the rotary shaft C, and connections, all arranged and combined to operate as set forth.

9. In combination with a series of rotating suspension-bars carrying cutters or agitators B *b*, and pinions C', the rack-bars K, carriages D and D', and the bevel-gears journaled therein, the gear J, having internal lug, and the

power-shaft I, having longitudinal groove *i*, all arranged and operating as and for the purposes set forth.

In testimony whereof we have hereunto set our hands in the presence of two subscribing witnesses.
